UNITED STATES PATENT OFFICE.

WILLIAM E. KEHOE, OF SAN FRANCISCO, CALIFORNIA.

DESIGN FOR A DISPLAY STAND.

Application filed August 20, 1924. Serial No. 10,506. Term of patent 7 years.

To all whom it may concern:

Be it known that I, WILLIAM E. KEHOE, a citizen of the United States, residing in city and county of San Francisco, State of California, have invented a new, original, and ornamental Design for Display Stands, of which the following is a specification, reference being had to the accompanying drawing, forming part thereof.

The figure is a perspective view showing my new design.

I claim:

The ornamental design for a display stand, as shown.

WILLIAM E. KEHOE.
